CONVERTIBLE CHAIR

Thomas H. Papworth, 552 Honore Drive,
New Orleans 22, La.

Filed July 16, 1964, Ser. No. 80,906

Term of patent 3½ years

(Cl. D15—1)

The side of the chair which is not shown is the same in appearance as the side that is shown.

I claim:

The ornamental design for a convertible chair, as shown and described.
